(57) **CLAIM**

The ornamental design for a portion of a slab comprising of particulate mineral mixture, as shown and described.

DESCRIPTION

The patent or application file contains at least one drawing executed in color. Copies of this patent or patent application publication with color drawing(s) will be provided by the Office upon request.

The sole FIGURE is a top plan view of a portion of a slab comprising of particulate mineral mixture, showing our new design. The depicted surface of the slab is flat.

The slab is suitable for use in living or working spaces (e.g., along a countertop, table, floor, or the like).
